CLAIM

The ornamental design for a rechargeable battery for portable wireless communication device, as shown and described.

DESCRIPTION

FIG. 1 is a top, front, and left side perspective view of a rechargeable battery for portable wireless communication device;

FIG. 2 is a top, rear, and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines shown in the drawings illustrate portions of the rechargeable battery for portable wireless communication device that form no part of the claimed design.
